UNITED STATES PATENT OFFICE.

EDWIN S. HEATH, OF CLINTONVILLE, PENNSYLVANIA.

DESIGN FOR A PINCUSHION.

Specification forming part of Design No. **11,230**, dated June 3, 1879; application filed April 16, 1879.
[Term of patent 14 years.]

To all whom it may concern:

Be it known that I, EDWIN S. HEATH, of Clintonville, State of Pennsylvania, have originated and designed a Pattern for a Pincushion, of which the following is a full, clear, and exact description, reference being had to the accompanying drawings, making a part of this specification.

Figure 1 is a perspective view, and Fig. 2 is a plan view.

A represents the body of the pincushion, formed in the shape of a turtle, with the head and legs projecting as if in the act of walking, and carrying upon its back a cushion, B. Within the turtle may be placed a coiled tape-

measure, with the end extending out through the mouth of the turtle and forming its tongue.

This makes a neat and unique design for a pincushion.

Having explained my invention, what I claim is—

The design for a pincushion, which is, essentially, in the form of a walking turtle, substantially as described, and shown in the accompanying drawings.

EDWIN S. HEATH.
